(57) **CLAIM**

We claim the ornamental design for a tubular tin purse, as shown and described.

DESCRIPTION

FIG. 1 illustrates a perspective view of a tubular tin purse of the present invention;

FIG. 2 illustrates a top view of the tubular tin purse of the present invention;

FIG. 3 illustrates a front view of the tubular tin purse of the present invention;

FIG. 4 illustrates a right side view of the tubular tin purse of the present invention, the left side view thereof being a mirror image of the right side view;

FIG. 5 illustrates a rear view of the tubular tin purse of the present invention; and,

FIG. 6 illustrates a bottom view of the tubular tin purse of the present invention.

The broken lines of FIGS. 1-6 are for illustrative purposes only and form no part of the claimed design.
